John H. Lane *L. Deane.* INVENTOR

This Attorney

UNITED STATES PATENT OFFICE.

JOHN H. LANEY, OF INDIANA, PENNSYLVANIA.

FARM-GATE.

SPECIFICATION forming part of Letters Patent No. 315,798, dated April 14, 1885.

Application filed July 1, 1884. (No model.)

To all whom it may concern:

Be it known that I, JOHN H. LANEY, a citizen of the United States, residing at Indiana, in the county of Indiana and State of Pennsylvania, have invented certain new and useful Improvements in Farm-Gates, of which the following is a specification, reference being had therein to the accompanying drawings.

Figure 1 is a front elevation of this device. Fig. 2 is a perspective view showing the main part of the gate separated from the swinging upright. Fig. 3 is a sectional view on line *x* of Fig. 1.

This invention belongs more especially to that class of gates styled "swinging," but is applicable to almost any farm-gate.

Its novelty consists in the construction and combination of the several parts, as will be now more fully and in detail set out and explained.

In the accompanying drawings, *A* denotes what may be called the "gate proper," or the main portion of the gate; and *B* and *C*, respectively, its front and rear uprights. This main part of the gate is connected to and secured upon its swinging upright *D* by means of the threaded bolt or rod *E*, which passes between the double pieces *c*, *c* and *d*, *d*, of which the uprights *C* and *D* are made, said rod being provided with nuts.

By means of any usual hinges, as *G*, the upright *D* is attached to the fence or other post *F*, and thus the gate can have the usual swinging motion.

The gate may be of any ordinary construction other than in the detail above stated, and in that on removing the bolt or rod *E* the main portion *A* is detachable from the upright *D*, and may have, on loosening the nuts on said bolts, vertical motion up and down said upright *D*, guided by means of the bolt *E* and the short and projecting fixed lower rail, *a*. At the lower end of the post or upright *C*, and in line with the lower rail, *a*, is a block, *a'*, which comes against the adjacent side of the upright *D*. In this construction the rail *a* and block *a'* afford very considerable help in staying and bracing all the parts when they are secured together. The short sliding upper rail or

bar, *a''*, at its rear passing between the double pieces of the uprights *C*, *D*, serves to steady the gate when said bar is slid between the pieces of upright *D*. The sliding rail *a''*, which is movable between the double pieces *b*, *b* of the front upright *B* and into the post *H* at the front end, serves as a catch or latch to hold the gate shut.

In swinging gates particularly, and in a general way in most gates, there is a tendency after some use for the forward part to sag and take the ground, and thus become hard to open and shut; besides this, rough work causes its speedy destruction.

In the construction now shown an easy and cheap way is disclosed by which the front portion of the gate can be always kept substantially on a level with the other parts. This is accomplished by means of the threaded bolt *E*, which is headed on the outer end, *e*, and passes between the vertical parts of the uprights *D* and *C*. It can be securely fixed to the upright *D* by the nut *e'*, and to the upright *C* by nuts *e''*, *e'''*. All these nuts may have washers. When now it is desired to raise the upright *B*, it is only necessary to move the upper rear slide, *a''*, forward, loosen the nuts, and then vertically lift the front post or upright to the desired level, when the nuts will be screwed firm, the slide *a''* moved back, and the tendency of the gate to sag will be rectified. The lower bar, *a*, and bottom rail, *a'*, act in a degree as pivots during this operation. The front part of the gate can be lowered in like manner, if desired; also, the gate part *A* can be fixed in position somewhat higher above the ground than is now shown. This is done by raising it bodily up and fixing it in position by the means above described. The upper rear slide, *a''*, may be between the next set of rails, if desired, and the bolt *E*, with its nuts, &c., may be between the next upper set of rails, in any position so long as their functions are preserved.

Having now described my invention, what I claim as new, and desire to secure by Letters Patent, is—

1. In a gate, the headed bolt or rod *E*, provided with nuts *e'*, *e''*, and *e'''*, and combined

with the uprights C B, swinging upright D, slide-bar a^2 , and fixed bar a , substantially as described.

2. The vertically-adjustable gate, its posts 5 F H, the swinging upright D, slide-bars a^2 a^3 , and the bolt E, with its clamp-nuts, all combined substantially as described.

3. In a gate, the combination of the upright C, the fixed and projecting guide-rail a , and 10 slide-rail a^2 with the bolt E and its clamp-nuts, and the swinging upright D, as described.

4. In a gate, the combination of the upright C, slide-rail a^2 , fixed guide-rail a , and block a' with the swinging upright D and the bolt E, provided with clamp-nuts, all as described. 15

In testimony whereof I affix my signature in presence of two witnesses.

JOHN H. LANEY.
